CLAIM

The ornamental design for a fusion splicer working tray as shown and described.

DESCRIPTION

FIG. 1 is a top perspective view of a fusion splicer working tray of our new design;

FIG. 2 is a rear perspective view thereof;

FIG. 3 is a front view thereof;

FIG. 4 is a rear view thereof;

FIG. 5 is a top plan view thereof;

FIG. 6 is a bottom view thereof;

FIG. 7 is a right side view thereof;

FIG. 8 is a left side view thereof;

FIG. 9 is a sectional view taken along the line 9-9 of FIG. 3;

FIG. 10 is a top perspective view thereof in use;

FIG. 11 is a front view thereof in use;

FIG. 12 is a rear view thereof in use;

FIG. 13 is a top plan view thereof in use;

FIG. 14 is a bottom view thereof in use;

FIG. 15 is a right side view thereof in use;

FIG. 16 is a left side view thereof in use;

FIG. 17 is an enlarged view defined by the line 1701-1701 of FIG. 13 in use;

FIG. 18 is an enlarged sectional view taken along the line 18-18 in FIG. 11 defined by the lines 1701-1701 of FIGS. 13 and 1801-1801 of FIG. 11 in use;

FIG. 19 is an enlarged sectional view taken along the line 19-19 in FIG. 11 defined by the lines 1701-1701 of FIGS. 13 and 1801-1801 of FIG. 11 in use;

(Continued)

FIG. 20 is an enlarged sectional view taken along the line 20-20 in FIG. 13 defined by the lines 1701-1701 of FIGS. 13 and 1801-1801 of FIG. 11 in use;

FIG. 21 is an enlarged sectional view taken along the line 21-21 in FIG. 13 defined by the lines 1701-1701 of FIGS. 13 and 1801-1801 of FIG. 11 in use;

FIG. 22 is an enlarged sectional view with an inner mechanism omitted taken along the line 22-22 in FIG. 11 defined by the line 1701-1701 of FIG. 13 in use;

FIG. 23 is an enlarged view defined by the lines 2301-2301 and 2302-2302 of FIG. 10 in use;

FIG. 24 is a top perspective view thereof in use, wherein the lid is closed; and,

FIG. 25 is a bottom perspective view thereof in use, wherein the lid is closed.

The broken lines show portions of a fusion splicer working tray that form no part of the claimed design.

The alternate long and short dash lines are merely the boundary lines between the claimed parts and the non-claimed parts.
